UNITED STATES PATENT OFFICE.

THOMAS C. JOHNSON, OF NEW HAVEN, CONNECTICUT, ASSIGNOR TO THE
WINCHESTER REPEATING ARMS COMPANY, OF SAME PLACE.

DESIGN FOR A CARTRIDGE PACKET OR HOLDER.

SPECIFICATION forming part of Design No. 27,657, dated September 21, 1897.

Application filed August 10, 1897. Serial No. 647,756. Term of patent 14 years.

To all whom it may concern:

Be it known that I, THOMAS C. JOHNSON, of New Haven, in the county of New Haven and State of Connecticut, have invented a new Design for Cartridge-Packets; and I do hereby declare the following, when taken in connection with the accompanying drawings and the letters of reference marked thereon, to be a full, clear, and exact description of the same, and which said drawings constitute part of this specification, and represent, in—

Figure 1, a view in elevation of the left-hand side of the packet; Fig. 2, a plan view thereof; Fig. 3, a view in elevation from the rear end thereof; Fig. 4, a view in vertical transverse section on the line *a b* of Fig. 1.

This invention relates to a design for cartridge-packets; and it consists in the form hereinafter shown and described.

My newly-designed cartridge-packet is tapering in side elevation and has a wide transversely-arranged passage A intersecting its closed upper end and extending farther down into the right-hand wall of the packet than into the left-hand wall thereof.

For convenience of description I shall refer to that portion of the passage extending into the right-hand wall of the packet as the "long" arm thereof and that portion of the passage

entering the left-hand wall of the packet as the "short" arm of the passage. This passage virtually divides the packet into a forward portion B and a rear portion B'. Below the short arm of the passage A is located a longitudinally-arranged tie C, while below the long arm of the passage is located a similar tie C', these ties connecting the forward and rear portions of the packet. The left-hand wall of the packet is formed at a point under the tie C with a longitudinally-arranged opening D. The upper ends of the rear and forward portions of the packet are rounded, while its lower end is open. The rear and forward ends of the packet are closed and the forward end formed with two vertically-arranged oppositely-located inwardly-setting ribs E E.

I claim—

The design for a cartridge-packet, as herein described and shown in the accompanying illustrations.

In testimony whereof I have signed this specification in the presence of two subscribing witnesses.

THOMAS C. JOHNSON.
